United States Patent Office

Des. 218,381
Patented Aug. 11, 1970

218,381

CONCRETE SAW

Richard E. Ten Eyck, Wichita, Kans., assignor to Clipper Manufacturing Company, Inc., Grandview, Mo., a corporation of Massachusetts

Filed Mar. 26, 1969, Ser. No. 16,476

Term of patent 14 years

Int. Cl. D15—05

U.S. Cl. D93—3

Fig. 1.

Fig. 2.

FIG. 1 is a top, rear perspective view illustrating the top of a concrete saw showing my new design; and

FIG. 2 is a front perspective view showing the top and opposite side thereof.

Portions appearing in dotted lines are for illustrative purposes only and form no part of my present design.

I claim:

The ornamental design for a concrete saw, as shown and described.
